CLAIM

The ornamental design for a solar power generation assembly, as shown and described.

DESCRIPTION

FIG. 1 is a left side elevation view of a solar power generation assembly showing my new design;

FIG. 2 is a front elevation view thereof;

FIG. 3 is a left and bottom side perspective view thereof;

FIG. 4 is a left and front side perspective view thereof; and,

FIG. 5 is a top and left side perspective view thereof.

The broken lines shown represent unclaimed subject matter and form no part of the claimed design.

The broken lines immediately adjacent to the claimed areas in the views represent the boundaries of the design. None of the broken lines form any part of the claimed design.

1 Claim, 5 Drawing Sheets
